UNITED STATES PATENT OFFICE.

CHARLES R. BARNES AND ALFRED GREEN, OF ROCHESTER, NEW YORK.

APPARATUS FOR PREVENTING COLLISIONS AT RAILWAY-CROSSINGS.

No. 828,871.

Specification of Letters Patent.

Patented Aug. 21, 1908.

Application filed November 12, 1903. Serial No. 180,861.

To all whom it may concern:

Be it known that we, CHARLES R. BARNES and ALFRED GREEN, of Rochester, in the county of Monroe and State of New York, have invented certain new and useful Improvements in Apparatus for Preventing Collisions at Railway-Crossings; and we do hereby declare the following to be a full, clear, and exact description of the same, reference being had to the accompanying drawings, forming a part of this specification, and to the reference characters marked thereon.

Our present invention relates to that class of devices employed at railway-crossings or junctions where two or more sets of tracks cross each other and which are adapted to prevent collisions between vehicles or trains on the separate tracks.

Our invention has for its object to provide means for signaling an approaching train on one track, together with mechanism for positively arresting said train, controlled by operating devices located at and operable from a point beyond said crossing; and it also comprehends devices adapted to be automatically operated by a train on the other track, where by the arresting mechanism before mentioned is automatically locked and unlocked by said train when moving toward and away from said crossing.

Further, our invention has for its object to provide an improved form of device for derailing a train, which may be moved into and out of the operative position and controlled in such movement by the mechanism heretofore mentioned, together with an improved form of an electromagnet for operating said device.

To these and other ends the invention consists in certain improvements and combinations of parts, all as will be hereinafter more fully described, the novel features being pointed out in the claims at the end of the specification.

In the drawings, Figure 1 is a diagrammatic view illustrating two intersecting railway-tracks and devices embodying the invention applied thereto. Figs. 2 and 3 are side and end elevations, respectively, of the derailing device. Fig. 4 is a side elevation of a mechanically-operated circuit-closer or switch. Fig. 5 is a similar view of a mechanically-operated circuit-breaker. Fig. 6 is a detail view of one of the locking devices.

Fig. 7 is a longitudinal sectional view of an electromagnet constructed in accordance with our invention.

Similar reference characters in the several figures indicate similar parts.

In illustrating our invention we have shown a railroad-crossing formed by the intersection of one set of tracks A A' with another set B B', the former for convenience in description being termed the "main line" and the latter the "secondary line," on which is arranged means for preventing the passage of a vehicle or train of cars when in the normal position and only capable of being operated by devices accessible at the opposite side of the main line or at a point beyond that side of the main line toward which a vehicle may be approaching, therefore requiring a conductor or other person to cross over the track A A', so that the approach of a train thereon in either direction may be ascertained.

The means or devices for preventing the passage of a vehicle on the secondary line consists in the present instance of derailing devices embodying a chair or seat 1, forming a section of one of the rails, and provided at its inner side with a groove 2, adapted to accommodate the flange of a car-wheel. Extending through the seat is a vertically-movable block 3, arranged at an angle to the groove 2 and projecting above the seat, as shown in Fig. 3, so that when a wheel is moving in one direction on the track its flange engaging with the block will cause the wheel to be deflected and the truck on which it is mounted to be derailed. To facilitate this operation, we form at the forward side of the block a second groove or recess 4, diverging from the groove 2 at the inner side of the rail. At the rear edge of the block, in line with the groove 2, is formed a notch 5, having an inclined bottom adapted to permit the flange of a wheel to pass onto the block and depress it automatically when moving over it in one direction. The means of holding the block in normal elevated position consists of a weighted lever-arm 6, journaled on a shaft 7, supported on brackets 8, secured to the lower side of the seat 1 and connected to a bell-crank lever 9, attached to the block by a short arm 10 and supported on a shaft 11, held in brackets 12, similar to brackets 8. The devices for operating the derailing mechanism consist of an electromagnet 17, having

a movable armature 18, connected by a slotted arm or link 19 to the bell-crank lever 9, as shown in Fig. 2.

The form of magnet illustrated is one designed to produce a large amount of magnetism, and its construction will be readily understood from an inspection of Fig. 7, in which is shown the casing (indicated by 70) provided with the removable top 71, having a central aperture, in which is fitted a sleeve or bushing 72. The latter is formed of brass, bronze, or other non-magnetic material, while the casing is formed of iron, and arranged therein is a coil or coils of wire 73, through which the current passes, the lines of magnetic force thereby produced being greatest in an inwardly-extending head or projection 74 on the bottom of the casing. The armature or core 18 is mounted upon a cross-head 75, supported on guides 76, which are of non-magnetic material, and projects within the sleeve, its lower end being recessed, as shown, to allow it to pass over the head 74 when approaching the limit of its inward movement.

In the illustration we have shown the devices just described located at each side of the main line of tracks, and situated at points beyond the main line relative to such devices are the signals and switches for closing the circuits through the before-mentioned magnets. The signal devices embody semaphore-arms 20 20', pivotally mounted upon upright supports 21 21', said arms being adapted to be held normally in a horizontal position, as shown, and to be operated into the position shown in dotted lines by means of handles or levers 22 22', pivoted to the supports at 23. These handles are connected by arms 24 24' to vertically-guided rods 25 25', which in turn are connected by rods 26 to their respective semaphore-arms. Surrounding the rods 25 are springs 27, which are placed under tension when the rods are drawn downwardly, so that the parts will be returned to their normal position when the handles 22 are released with the semaphore-arms set in the danger position. A night-signal is also controlled by the movement of the arms, the outer ends thereof having frames containing colored glass 28, adapted to be moved into and out of alignment with boxes mounted upon the support 21 21' and provided with lamps 29, as indicated in Fig. 1.

In Fig. 1 we have shown the secondary railway-line as consisting of but a single track formed by the rails B B', and therefore there is shown a vehicle-arresting device arranged in each of said rails and located at opposite sides of the main line; but if the secondary line were composed of two or more tracks it will be understood that said devices would be located in the same relative position, so as to arrest vehicles traveling in opposite directions thereon. The electromagnets for operating the vehicle-arresting devices are indi-

cated by 17 and 117, the former being connected by a wire 17' to a contact member *b* on the support 21, located relatively to the derailing device at a point at the opposite side of the main line of tracks. The means 70 for closing the circuit through the contact member *b* is the operating-handle 22, to which is connected the wire *c*, leading from any suitable form of current-generator, and as these devices are adapted particularly to 75 be used at the intersection of street-railway tracks and those of steam-operated railways the wire *c* may lead directly from the usual trolley-wire C, and the circuit leading from the magnet 17 may be closed through a wire 80 *c'* either to the ground or to one of the rails B or B' usually included in such circuit. A similar circuit leads through the magnet 117, and it consists of a wire *d*, leading from the trolley-wire or other source of supply to the 85 semaphore-operating arm 22', the wire *e*, leading from the contact *f*, and the wire *e'*, corresponding to the wire *c'*. The signal-lamps 29, before referred to, may be the usual incandescent or other form of electric 90 lights operated by current flowing through the derived circuits *g* and *g'*, as will be understood. From the arrangement of the circuits extending through the electromagnets it will be seen that they are capable of being 95 operated independently and only by closing the respective arms 22 and 22', so that when one or the other is operated its respective vehicle-arresting device will be moved into the inoperative position, at which time the 100 semaphore-arm 20 is also lowered to indicate a clear track. In order to prevent the operation of the vehicle arresting or derailing devices when a train is approaching on the main line within a certain distance at either side of 105 the crossing, we provide locking devices for the operating handles or levers 22 22', which are arranged in electric circuits including 110 switches or circuit-closers located at a suitable distance from the crossing and adapted 115 to be automatically operated by the passage of a train on the main line. In connection with these circuits we also employ two separate switches or circuit-breakers for each circuit-closer, one of which is arranged relatively to the circuit-closer at a point beyond the secondary line to release said circuit-closer and the devices controlled thereby after a train has passed the crossing and the other located at a point in front of the circuit-closer, so that the circuit through the latter may be opened and all of the parts returned to the normal position instead of being left in the locked or operated condition, as would be the case if an engine or train of cars 120 approached the crossing and operated the circuit-closer and then backed away from the crossing.

Arranged on the supports 21 21' are electromagnets 35 35' 36 36' in the form of solen- 125

oids, as shown in Fig. 6, and having armatures or cores 13, provided with pins or points 14, adapted when the armature is operated to project through suitable apertures 5 arranged in the arms or levers 22 22' to prevent their being moved either to change the position of the semaphore-arms or to close the circuits through the magnets 17 and 117. Located at either side of the crossing and at 10 distances ranging from one to two thousand feet therefrom are provided circuit-closing devices, which may be of any desired form, the one we deem preferable being illustrated in Fig. 4 and so constructed that it is operated only by a train moving in one direction and when so operated is automatically retained until released by the operation of one of the circuit-breakers, to be further described. The circuit-closers are indicated by 15 H and I in the diagrammatic illustration in Fig. 1, and they each embody electromagnets 36, the one provided in the circuit-closer H being arranged in a circuit 37, leading from the trolley-wire or source of current-supply C to the magnets of the locking devices 35' 35 and thence to the ground through the circuit-breakers h h'. The magnet 36 on the closing device I is arranged in the circuit composed of the wire 38, leading from the source of current-supply 36' 36 to the magnets and thence through the circuit-breakers i i' to the ground. Both of these circuits lead through insulated contact-plates 41 41', which are connected by a movable contact 42 when the 20 circuit-closers H I are operated, and as the circuit-closers are only adapted to be operated by vehicles moving in one direction we provide an operating-link 51, pivotally connected at its ends to the bar 45 and to one of the chairs 43, having at one side a finger or projection 52, which rests on the end of the lever 46, so that the latter is only actuated by the movement of the plate when the latter is operated in the direction indicated by the 25 arrow.

Belted to one of the rails A A' of the main line are chairs or blocks 43, on which are pivoted links 44, supporting at their upper ends a longitudinally-movable bar or member 45. Pivoted on one of these blocks is a lever 46, one end of which is connected, by means of a link 48, to a frame 49, carrying the contact member 42. The frame 49 is guided in its 30 vertical movement by means of rods 50, and it is normally operated to hold the contact member 42 out of engagement with the contacts 41 41' by means of the weighted end 55 of the lever 46.

The magnet 36 is preferably constructed in 35 the form of a solenoid, and the frame 49 is provided with a core or armature 56, projecting into the coil of the magnet and adapted to hold the contact 42 in the operated position and to retain the circuit through the magnet 55 in the closed position until said circuit is

broken at some other point, when the parts will be allowed to return to the normal position by the action of the weighted end of the lever 55.

The circuit-breakers (indicated on the diagrammatic view by the letters h h' and i i') are constructed as shown in Fig. 5 and embody the blocks 57, secured to one of the rails by the bolts 58, and the longitudinally-movable bar 59, pivotally attached to the blocks 57 by 70 links 60, whereby it is free to be moved longitudinally of the rail in both directions and to be normally held in the position shown in said figure by a weighted lever-arm 61. Attached to and movable with one of the links 80 60 is a movable contact-finger 61, co-operating with a relatively stationary contact-point 63 and adapted when the bar 59 is moved in one direction to remain in engagement with the contact-point and when said bar is moved in 85 the opposite direction to be disconnected therefrom and to break the circuit leading therethrough. The contact-point 63 is arranged on a pivoted arm 64, which is permitted a limited movement between stop-pins 65, whereby it may accommodate itself to the movable member when the latter is operated. In both the circuit closing and breaking devices we have illustrated their contact-points as arranged in proximity to 90 their operating devices; but it will of course be understood that they may be arranged at a distance therefrom, if desired, and any suitable form of operating connections arranged between these parts.

The operation of the circuits and the various devices controlled thereby will be readily understood from the foregoing description, taken in connection with the diagrammatic illustration shown in Fig. 1; but in order to describe the successive operation of the various parts let the operation of the vehicle-arresting devices be first considered without reference to the means for locking or controlling them. If a vehicle or train on 100 the secondary line is approaching from the main line from the direction indicated by the arrow in Fig. 1, it must be brought to a stop before the derailing device located in the rail B' is reached. To remove this obstruction, the conductor or other authorized person must pass over the tracks of the main line and operate the arm or handle 22 to move the semaphore-arm 20 out of the danger position. This operation closes the circuit through the wire c, contact b, wire 17, the magnet 17 and the return through the wire c', and one of the rails causing the armature 18 of the magnet to be operated and the block 3 of the derailing device to be retracted beneath the surface of the rail B', allowing the car-wheels to pass along the track in the usual manner. After the car has passed over the derailing device the operator releases the handle 22, when it is re- 115 120 125 130

turned to the normal position by the spring 27 breaking the circuit before described and allowing the weighted lever-arm 6 to restore the block 3 to its normal position. The operation of the magnet 117 is the same as that of the magnet just described, the circuit being completed through it by means of the wire *d*, the lever 22', the contact *f*, and the wires *e'c'* and one of the rails. When a train is approaching the crossing on the main line from either direction, it will operate one of the circuit-closing devices *H* or *I*, and if approaching from a direction at the right-hand side of Fig. 1 the first wheel engaging the bar 45 will move it longitudinally of the track in the direction indicated by the arrow in Fig. 4, causing the operation of the lever 46 and the engagement of the contact-plate 42 with the plates 41 41', closing the circuit in the wire 37, when, as before explained, the magnet 36 will retain the parts in the operated position, allowing the current to flow from the source of supply *C* through the wire 37 to the magnets 35 and 35', to the contact-breakers *h* and *h'*, the former of which is located at or near the crossing, but at the opposite side thereof relatively to its circuit-closer *H*, and being adapted to be operated to separate the contact-points 62 and 63 to break the circuit after the train has passed the crossing. The circuit-breaker *h'* being arranged at a greater distance from the crossing than its circuit-closer and having its contact-points 62 and 63 arranged to be operated to break the circuit by a train moving in a direction toward the right-hand side of Fig. 1 serves to restore the circuit-closer *H* to its normal position in case the breaker *h* is not operated, as would occur in such instances were an engine or train moved into proximity with the crossing and then backed away. A train moving toward the crossing from the left-hand side of Fig. 1 would operate the circuit-closer *I*, allowing the circuit to flow from the source of supply *C* through the wire 38 to the magnets 36 and 36', thence through circuit-breakers *i* *i'* to ground. When the bar 45 of the circuit-closer *I* has been operated and the current allowed to flow through its magnet 36, the parts thereof are held in the operative position until the circuit-breaker *i* is operated, permitting the armatures of the magnets 35 35' to be restored to the normal position and the levers 22 22' unlocked. The circuit-breaker *i'* corresponds to and is similar to the one, *h'*, and is adapted to be operated to break the circuit and allow the parts to be restored to the normal position if for any reason the car or train passes by and returns over the circuit-closer *I* without operating the circuit-breaker *i*.

The devices we have described for arresting the movement of a vehicle or train upon a secondary track are termed "derailing de-

vices;" but this expression simply applies to this means of stopping a car in its onward movement; but it will be understood that our invention comprehends other means for controlling the movement of a vehicle, and while the application of the devices are illustrated as employed at the crossing-point of two or more railroad-lines it will also be understood that they are equally adapted to be employed for arresting vehicles—such as one or more cars, engines, or the like—at other points where it is demanded that operators shall bring their vehicles to a full stop.

We claim as our invention—

1. In an apparatus for preventing collisions between vehicles on intersecting lines of railways, the combination with a vehicle-arrestor located in one track at each side of the point of intersection of the two tracks, of electromagnetic devices for operating each arrestor, a circuit, embodying a current-generator, connected to each of said operating means and controlling device, in each circuit located relatively to said operating means at the other side of the point of intersection. 90

2. An apparatus for preventing collisions between vehicles on intersecting lines of railways, embodying means for preventing the movement of a vehicle on one line of track and located at one side of its point of intersection with the other track and an electromagnetic operating said means, a circuit leading through the magnet and having contacts located beyond the point of intersection of the tracks and a manually-operated switch 100 controlling said contacts.

3. An apparatus for preventing collisions between vehicles on intersecting lines of railways, embodying means for controlling the movement of a vehicle on one line of track, 105 located at one side of its point of intersection with the other track, an electromagnet operating said means, and a circuit leading through the magnet having contacts, located beyond the point of intersection of the tracks, a manually-operated switch controlling said contacts and a signal operated by the switch.

4. In an apparatus for preventing collisions between vehicles on intersecting lines of railways, the combination with means for arresting the movement of a vehicle on one line of track and electromagnetic devices for moving said means into the inoperative position, of devices actuated by engagement with a vehicle on the other line of track for preventing the operation of said electromagnetic devices. 115

5. In an apparatus for preventing collisions between vehicles on intersecting lines of railways, the combination with means for arresting the movement of a vehicle on one line of track and devices for moving said means into the inoperative position, of electromagnetic locking devices for said means, circuits for said devices including a current-gener- 125

ator, and contacts located in proximity to the other track at each side of the point of intersection of said tracks and adapted to be operated by engagement with a vehicle to prevent the movement of the vehicle-arresting means.

6. The combination with a main-line railway-track and a secondary line intersecting therewith, vehicle-arresting devices on the secondary line and means for operating said devices, of electrically-operated mechanism for controlling the vehicle-arresting devices comprising a circuit embodying a source of current, a circuit-closer and a circuit-breaker adapted to be operated by a vehicle on the main line to open and close the circuits.

7. The combination with a main-line railway-track and a secondary line intersecting therewith, vehicle-arresting devices on the latter line and means for operating said devices, of electrically-operated devices, for controlling the vehicle-arresting devices, arranged in a normally open circuit embodying a source of current and having a circuit-closer and circuit-breaker adapted to be operated by a vehicle on the main-line track and located at opposite sides of the point of intersection of said tracks.

8. The combination with a main-line railway-track and a secondary line intersecting therewith, vehicle-arresting devices on the latter line and means for operating said devices, of electrically-operated devices, for controlling the vehicle-arresting devices, arranged in a circuit embodying a source of current, a normally open circuit-closer and a circuit-breaker arranged in said circuit and adapted to be operated by a vehicle on the main line.

40 9. The combination with a main-line railway-track and a secondary line intersecting therewith, vehicle-arresting devices on the latter line and means for operating said devices, of electrically-operated devices, for controlling the vehicle-arresting devices, arranged in a normally open circuit embodying a source of current, a circuit-closer, and two circuit-breakers arranged one at each side of the circuit-closer both the latter and the circuit-breakers being adapted to be operated by a vehicle on the main line.

10. The combination with a main-line railway-track and a secondary line intersecting therewith, vehicle-arresting devices on the latter line and means for operating said devices, of electrically-operated devices, for controlling the vehicle-arresting devices, arranged in a normally open circuit embodying a source of current, a circuit-closer located at one side of the point of intersection of the tracks, and two circuit-breakers arranged one at each side of the circuit-closer, one being located at a point beyond the point of intersection of the tracks, and adapted to be operated by a vehicle on the main-line track.

11. The combination with a main-line railway-track and a secondary line intersecting therewith, vehicle-arresting devices on the latter line and means for operating said devices, of electrically-operated devices, for controlling the vehicle-arresting devices, arranged in a circuit embodying a source of current, a circuit-closer normally open and having an electromagnet located in the circuit and operating to retain it in the closed position and a switch for breaking the circuit through the magnet and means for returning the circuit-closer to its normal position.

12. The combination with a main-line railway-track and a secondary line intersecting therewith, a plurality of vehicle-arresting devices on the latter line and separate means for operating each of said devices, of separate electrically-operated locking devices for controlling the vehicle-arresting device embodying a circuit including the separate locking devices, a normally open circuit-closer and a circuit-breaker both of which are adapted to be operated by a vehicle on the main-line track.

13. The combination with a main-line railway-track and a secondary line intersecting therewith, vehicle-arresting devices located at opposite sides of the main line and separate means for operating each, of a separate electrically-operated locking device for each arresting device, a circuit leading through the locking devices and embodying a source of current, and a normally open circuit-closer adapted to be operated by a vehicle on the main-line track, a magnet arranged in the circuit and adapted to retain the circuit-closer in the operated position, two switches located in the circuit, one at each side of the circuit-closer, and adapted to be operated by vehicles moving in opposite directions.

14. The combination with a main-line railway-track and a secondary line intersecting therewith, vehicle-arresting devices located at opposite sides of the main line and separate means for operating each, of a separate electrically-operated locking device for each arresting device, a circuit leading through the locking devices and embodying a source of current, a normally open circuit-closer and a switch arranged in the circuit and located beyond the secondary track and adapted to be operated by a vehicle moving on the main track in one direction, a second switch also arranged in the circuit and located at the other side of the circuit-closer and adapted to be operated by a vehicle moving on said track in the opposite direction and a magnet located in the circuit and operating to retain the circuit-closer in the operated position until the circuit is broken at one of said switches.

15. The combination with a main-line railway-track and a secondary line intersecting therewith, vehicle-arresting devices located

at opposite sides of the main line and separate means for operating each, of separate electrically-operated locking devices for each arresting device, circuits leading through the locking devices and each embodying a source of current and a normally open circuit-closer one of which is arranged at each side of the secondary track, a switch arranged in each circuit and located relatively to their respective circuit-closers at points beyond the secondary track and magnets arranged in the circuits and operating to retain the circuit-closers in the operated position.

arresting device, circuits leading through the locking devices and each embodying a source of current and a normally open circuit-closer one of which is arranged at each side of the secondary track, a switch arranged in each circuit and located relatively to their respective circuit-closers at points beyond the secondary track and separate switches arranged in the two circuits and located outside of their respective circuit-closers and magnets in each circuit for retaining a circuit-closer in operated position until released by the operation of one of said switches.

16. The combination with a main-line rail-way-track and a secondary line intersecting therewith, vehicle-arresting devices located at opposite sides of the main line and separate means for operating each, of separate electrically-operated locking devices for each
